UNITED STATES PATENT OFFICE.

WILLIAM A. BRAUN, OF FORT WAYNE, INDIANA, ASSIGNOR OF ONE-HALF TO FREMONT
L. JONES, OF FORT WAYNE, INDIANA.

ELECTRICAL SAD-IRON.

941,342.

Specification of Letters Patent. Patented Nov. 23, 1909.

Application filed January 20, 1908. Serial No. 411,573.

To all whom it may concern:

Be it known that I, WILLIAM A. BRAUN, a citizen of the United States of America, and resident of Fort Wayne, in the county of Allen and State of Indiana, have invented certain new and useful Improvements in Electrical Sad-Irons, of which the following is a specification.

This invention relates to improvements in electrically heated sad-irons, and the object thereof is to provide automatic apparatus in connection therewith for breaking the electrical circuit at times when the iron becomes heated above its normal working temperature, so that the flow of electrical current is entirely stopped and economy thereby effected. I accomplish this object by the construction illustrated in the accompanying drawings in which—

20 Figure 1 is a perspective view of the invention showing the exterior of the iron; and Fig. 2 is a diagram showing the base of the iron, the heating element therein, the circuit breaking apparatus, and the electrical appurtenances.

Similar numerals of reference indicate corresponding parts in both views, and referring now to the same:

1 is the base of the iron, which is made hollow, and 2 is a cover therefor which is secured in any suitable manner and is surmounted with a handle 3. Within the interior of the base is an electrical heating member 4 of any well known construction, 35 and one end of the heating member is connected to an insulated terminal 5 which is secured in the back of the iron with one of its ends extending through the wall and exposing upon the exterior of the iron a contact point 6. The other end of the heating member 4 is connected with the line conductor 7. At the back of the iron, upon the opposite sides from the terminal 5, are insulators 9 and 10 respectively, and upon these 40 is attached an expandible bridge consisting of a curved metallic plate 11. In the middle of this plate is fixed an internally threaded stud 12 which affords support for an adjusting screw 13 the inner end of which is 45 adapted to rest against the contact point 6 of the terminal 5 when the bridge is in normal state of temperature. One end of the bridge is electrically connected with an insulated terminal 14 which has connection with the 50 other line conductor 8. A condenser 15 has

connection at one side by means of a wire 16, with the conductor 8 and at the other side by means of the wire 17 with the terminal 5.

In the operation of this invention, the line conductors are connected with any suitable 60 source of electrical current, and as the current flows through the circuit formed by the conductor 7, heating member, 4, terminal 5, the screw 13, bridge 11, terminal 14 and conductor 8, the base of the iron becomes heated. 65 When the temperature of the iron rises above its normal working temperature, the bridge 11 becomes expanded by conduction of heat from the iron, and, being curved, presses outward and thereby breaks the connection 70 of the screw 13 with the contact point 6, thus opening the electrical circuit. The function of the condenser is to prevent the current from forming an arc when the contact is broken. When the temperature of the iron 75 shall have decreased to a point below its normal working temperature, the bridge 11 will consequently become contracted so that the screw 13 again rests against the contact point 6 so that the electrical circuit is complete 80 and the flow of current resumed. Thus it will be understood that the breaking of the electrical circuit is dependent upon the excessive heat of the iron, and at such times the flow of current ceases entirely, and the 85 closing of the circuit is dependent upon the reduction in temperature of the iron.

Having described my invention, what I claim as new and desire to secure by Letters Patent is:—

1. In a device of the class described, a hollow iron base; an electrical heating member therein; an insulated contact terminal having a point exposed exterior of the iron, and electrical connection with the heating member; an expanding member having its ends attached in connection with the iron and having normal contact with said terminal; and line conductors, one having connection with the heating member, and the other with the expanding member the said expanding member forming a part of the electrical circuit for energizing the heating member, said expanding member being adapted to be actuated by heat emanating from the heating member.

2. In a device of the class described, a hollow iron base; a heating member therein; an insulated terminal having a contact point and electrical connection with the heating

member; an expanding member consisting of a curved plate with an adjusting screw therein, the said plate having its ends in fixed connection with the iron base but insulated therefrom and normally having connection by means of its screw with said terminal; two line conductors, one connected with the heating member and the other with the expanding member; and a condenser, one side of which has connection with the expanding member, and the other side with the terminal the said expanding member forming a part of the electrical member, said expanding member being adapted to be actuated by heat emanating from the heating member.

3. In a device of the class described, a hollow iron base; an electrical heating member therein; an insulated terminal having a contact point and electrical connection with the heating member; an expanding member in connection with the base and having normally a contact with said terminal; and line conductors, one having connection with the heating member, and the other with the expanding member, the said conductors, heating member, terminal and expanding member each forming a part of the electrical circuit for energizing the heating member, said expanding member being adapted to move from contact with the terminal when the base becomes heated above its normal working temperature by heat emanating from the heating member.
4. In a device of the class described, a hollow iron base; a heating member therein; an insulated terminal extending through the wall of the base and having electrical connection with the heating member; an expanding member external of the base consisting of a curved plate with its ends secured to the base and having contact with

the terminal when the base is at its normal working temperature; and two line conductors, one connected with the heating member and the other with the expanding member; the latter being adapted to move from contact with the terminal when the base is above its normal working temperature said expanding member forming a part of the electrical circuit for energizing the heating member, said expanding member being adapted to be actuated by heat emanating from the heating member.

5. In apparatus of the class described, a hollow iron base; an electrical heating member therein; an expanding member attached to the iron and having a movable electrical contact in connection with the heating member; and suitable electrical conductors, one in connection with the heating member and the other with the expanding member, each forming a part of the electrical circuit for energizing the heating member, said expanding member being adapted to be actuated by heat emanating from the heating member.

6. In apparatus of the class described, a hollow iron; an electrical heating member; an expanding member; and two electrical conductors, the heating and expanding members being both attached to and carried by the iron and connected in electrical series with the conductors to form an electrical circuit for energizing the heating member, said expanding member being adapted to break the circuit when sufficiently expanded by heat emanating from the heating member.

In testimony whereof I affix my signature, in presence of two witnesses.

WILLIAM A. BRAUN.
